UNITED STATES PATENT OFFICE.

LOUIS JULLIEN, OF PASSY, FRANCE, ASSIGNOR TO JOSEPH WILD & CO.,
OF NEW YORK, N. Y.

DESIGN FOR A CARPET-PATTERN.

Specification forming part of Design No. 5,787, dated April 16, 1872.

Specification describing a new and original Design for a Carpet, invented by LOUIS JULLIEN, of Passy, department of the Seine, Republic of France.

The accompanying photograph represents my new design.

This invention relates to a new floral design to be applied to carpets. The foliage in the same is formed to somewhat resemble a cornu-

copia, from which the flowers issue, and with which they are connected by projecting scrolls, as shown.

I claim as my invention --

The floral design for a carpet, as shown.
L. JULLIEN.
